UNITED STATES PATENT OFFICE

HORACE F. GRUMAN, OF ST. LOUIS, MISSOURI, ASSIGNOR TO LEWIS INVISIBLE STITCH MACHINE COMPANY, OF ST. LOUIS, MISSOURI, A CORPORATION OF MAINE
STITCH FORMING MECHANISM FOR SEWING MACHINES

Original application filed January 31, 1931, Serial No. 512,661. Divided and this application filed September 19, 1931. Serial No. 563,842.

This invention relates to new and useful improvements in stitch forming mechanisms for sewing machines, and constitutes a division of my co-pending application Serial No. 512,661, filed Jan. 31, 1931, for sewing machines.

Among the several objects of my invention are to provide a stitch forming mechanism which is capable of being readily applied within a tubular work arm of comparatively small cross sectional area; to provide an oscillatory needle shaft which extends longitudinally of the arm and to which the needle is fixed for reciprocatory movements in a plane at right angles to the axis of the shaft; to provide a 4-motion threaded looper for cooperation with the needle; to provide driving connections between the needle shaft and the looper for imparting loop entering and loop shedding movements to the looper; to provide means other than the needle shaft for imparting needle avoiding movements to the looper, and to provide such a mechanism which is composed of but few parts and is therefore simple in construction and cheap to manufacture.

With these and other objects in view which will more fully appear, the nature of the invention will be more clearly understood by following the description, the appended claims, and the several views illustrated in the accompanying drawings.

In the drawings:—

Figure 1 is a top plan view of a work arm showing the application of my invention therein,

Figure 2 is a detail vertical sectional view showing the driving connections for the needle shaft and the looper,

Figure 3 is a perspective view of a bracket on which the looper mechanism is mounted,

Figure 4 is a perspective view of the looper carrier,

Figure 5 is a perspective view of the looper and the looper holder,

Figure 6 is a perspective view of the guard plate which retains the looper carrier in its bearing, and

Figure 7 is a detail horizontal sectional

view showing the means for oscillating the looper carrier from the needle shaft.

Like reference numerals designate corresponding parts throughout the several figures of the drawings.

In the accompanying drawings, I have disclosed my invention as mounted within a tubular work arm 10 of comparatively small cross sectional area. A bracket 11 is mounted within the arm 10 and extends longitudinally thereof. This bracket is removably attached to the bottom 12 of the arm by screws 13, 13 and includes spaced front and rear bearings 14, 15 and an intermediate bearing 16, the rear and intermediate bearings being formed in a post 17 which is integral with the bracket 11 and extends upwardly into the arm 10. Dowel pins 18, 18 which act as centering pins also connect the bottom 12 of the arm and the bracket 11.

Journaled in the bearings above described is an oscillatory needle shaft 19 which of course extends longitudinally of the work arm. The shaft is retained against longitudinal movements relative to the bracket 11 by means of a collar 20 which engages the front bearing 14 and by the hub 21 of a needle arm 22 which is clamped to the shaft on that side of the bearing 16 opposite the bearing 15. The needle arm 22 extends radially from the shaft and thence rearwardly past the right hand side of the bearing post 17, and attached to the free end of the needle arm is a curved needle 23 which oscillates in an arcuate path extending above the shaft 19 and in a vertical plane at right angles to the longitudinal axis of said shaft. Thus the needle 23 oscillates wholly within the confines of the cross sectional area of the work arm 10.

Cooperating with the needle 23 to form a line of Grover and Baker stitches is a 4-motion threaded looper 24 which is rigidly connected, preferably integrally, to a looper holder 25 having beveled side edges 26, 26. A looper carrier 27 is mounted for oscillatory movements in a recessed bearing 28 formed in the post 17, the longitudinal axis of the bearing 28 being in a horizontal plane and in a plane at right angles to the longitudinal

axis of the needle shaft 19, and the bearing being located on the left hand side of said shaft. It will also be noted that the longitudinal axis of the bearing 28 is in the vertical plane containing the path of travel of the needle 23. The looper carrier 27 is provided on its outer face with a radially extending groove or guiding channel 29 in which the looper holder 25 is mounted for straight line reciprocatory movements. The looper 24 is disposed above the holder 25 and above the carrier 27 and has its loop taking movement toward the operator or in other words, in a direction opposite the free end of the work arm. When the carrier 27 is oscillated the looper 24 is given its loop taking and loop shedding movements or in other words its forward and backward travel, and when the looper holder 25 is reciprocated in said carrier the looper is given its needle avoiding movements which, as is well known in the art, is necessary to insure the flat setting of a looper thread in the stitches being formed. A guard plate 30 which is removably attached to the left hand face of the bearing post 17 projects slightly beyond the bearing 28 to retain the looper carrier 27 in said bearing.

In order to oscillate the looper carrier 27 and thereby impart loop entering and loop shedding movements to the looper 24, I have fixedly mounted a driving bevel gear 31 on the rear end of the needle shaft 19 and have protected said gear from lint and the like by locating said gear in a recess 32 formed in the bearing post 17. The gear 31 is in constant mesh with a driven gear 33 fixed to the inner face of the looper carrier 27 to oscillate the latter upon oscillation of the needle shaft 19. The gear coupling 31, 33 is a 1-to-1 coupling and consequently the looper travel mechanism is timed with the needle travel mechanism whereby the loop taking or loop entering movement of the looper begins simultaneously with the retractile movement of the needle, and the loop shedding movement of the looper begins simultaneously with the penetrating or forward stroke of the needle.

In order to impart needle avoiding movements to the looper 24, I have provided a vertical link 34 having its lower end pivotally connected to the front end of a lever 35 which extends longitudinally within the work arm 10 on the left side of the needle shaft 19, and is fulcrumed intermediate its ends on a horizontal pivot screw 36 mounted on the bracket 11. The rear end of the lever 35 is provided with an upstanding arm 37 having substantially horizontal arms 38, 39 and forming therebetween a slot 40. A slide block 41 is fulcrumed on a pivot screw 42 fixed to the looper holder 25, and this block 41 is mounted in the slot 40 for sliding movements relative to the arms 38, 39. Thus when the vertical link 34 is oscillated lengthwise, the

lever 35 will be correspondingly oscillated, and therefore the looper holder 25 will be raised and lowered along the groove or guiding channel 29 of the looper carrier 27 and thereby imparting needle avoiding movements to the looper. The parts are timed so that the needle avoiding movements of the looper will be imparted at opposite ends of the looper travel. The looper in its forward or loop taking movement passes under the needle and in its backward or loop shedding movement passes over the needle.

It is of course to be understood that the details of structure and arrangements of parts may be variously changed and modified without departing from the spirit and scope of my invention.

I claim:—

1. In a sewing machine, the combination with an oscillatory shaft; of a radially extending arm fixed to said shaft; a curved needle fixed to said arm for oscillation in a plane at right angles to the longitudinal axis of the shaft; a 4-motion threaded looper independent of the shaft and cooperating with the needle, driving connections between the shaft and the looper for imparting loop-taking and loop-shedding movements to the looper, and means separate from the shaft for imparting needle-avoiding movements to the looper.

2. In a sewing machine, the combination with an oscillatory shaft; of a radially extending arm fixed to said shaft; a curved needle fixed to said arm for oscillation in a plane at right angles to the longitudinal axis of the shaft; a 4-motion threaded looper independent of the shaft and cooperating with the needle, driving connections between the shaft and the looper for imparting loop-taking and loop-shedding movements to the looper including an oscillatory looper carrier movable in a plane at right angles to the path of needle movement and a gear coupling between the shaft and the carrier, and means separate from the shaft for imparting needle-avoiding movements to the looper.

3. In a sewing machine, the combination with an oscillatory shaft; of a radially extending arm fixed to said shaft; a curved needle fixed to said arm for oscillation in a plane at right angles to the longitudinal axis of the shaft; an oscillatory looper carrier movable in a plane at right angles to the path of needle movement, a looper holder mounted in the carrier for bodily movements therewith and for radial reciprocatory movements relative thereto, a threaded looper fixed to said holder, driving connections between the shaft and carrier for oscillating the latter to impart loop-taking and loop-shedding movements to the looper, and means connected to the looper holder for imparting needle avoiding movements to the looper.

4. In a sewing machine, the combination

with an oscillatory shaft; of a radially extending arm fixed to said shaft; a curved needle fixed to said arm for oscillation in a plane at right angles to the longitudinal axis 5 of the shaft; an oscillatory looper carrier movable in a plane at right angles to the path of needle movement, said carrier being provided with a radially disposed guiding channel, a looper holder slidably mounted in the 10 channel of the carrier for bodily movements with the carrier and for radial reciprocatory movements relative thereto, a threaded looper fixed to said holder, driving connections between the shaft and carrier for oscillating 15 the latter to impart loop-taking and loop-shedding movements to the looper, and means connected to the looper holder for imparting needle-avoiding movements to the looper.

5. In a sewing machine, the combination 20 with an oscillatory shaft; of a radially extending arm fixed to said shaft; a curved needle fixed to said arm for oscillation in a plane at right angles to the longitudinal axis of the shaft; a 4-motion threaded looper 25 cooperating with the needle; and means for operating said looper comprising a fixed casing having a circular bearing, a looper carrier mounted in the bearing of the casing for oscillations about an axis parallel with the 30 plane of needle reciprocations, said carrier being provided with a radially extending guiding channel, a looper holder mounted in said guiding channel for bodily movements with the carrier and for radial reciprocatory 35 movements relative thereto, driving connections between the shaft and the looper for imparting loop-taking and loop-shedding movements to the looper, and means separate from the shaft for imparting needle-avoiding 40 movements to the looper.

In testimony whereof I affix my signature.
HORACE F. GRUMAN.
